UNITED STATES PATENT OFFICE

2,535,216

APPARATUS FOR DRYING

Walter W. Letts, Northville, N. Y.

Application August 10, 1949, Serial No. 109,449

6 Claims. (Cl. 34—57)

1

This invention relates to improvements in apparatus for drying and is directed more particularly to the provision of a novel means for drying a material in its granulated form such as straw grain, sawdust, or the like.

A principal object of my invention is to provide an improved construction of the type in which means carries the material to be dried through the dryer of the invention where it is subjected to hot air and discharged therefrom.

The retention of moisture in many materials often results in objectionable difficulties. For example, the retention of water in certain materials such as grain during shipment adds appreciably to the cost of such shipment. Thus the device of my invention has definite uses in the elimination of such difficulties.

Other prime objects of my invention include: first, the provision of a simplified construction and arrangement of an apparatus for drying a material in its granulated form which is strong, durable and compact in its structure and is distinctive in its appearance; second, the securing of a higher degree of accuracy in the manner of work performed therewith than has heretofore been possible with prior devices known in the art; third, the attainment of a higher degree of speed of construction and assembly of the device due to its simplification in design and its unique composition of parts; fourth, the attainment of a flexibility or a capability of adjustment by which a large variety of work can be produced by means of the same device; fifth, the provision of an improved drying apparatus which may be made more economically and with fewer operations in the manufacture of its parts, as well as in the assembly of the same, than prior devices known in the art; and sixth, the provision of a construction which may be readily installed with respect to the various purposes for which it is intended.

These objects I accomplish by means of such structure and relative arrangement of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claims hereunto annexed and more fully de-

2

scribed and referred to in connection with the accompanying drawings wherein:

Fig. 1 is a side elevational view of the device of my invention;

Fig. 2 is a top plan view of the device shown in Fig. 1.

Fig. 3 is an end elevational view of the device of the invention looking at the forward or front end thereof, and

Fig. 4 is a sectional elevational view along the line 4—4 of Fig. 1.

In the above mentioned drawings annexed hereto and forming a part of this specification, I have shown but one embodiment of my invention which is deemed preferable, but it is to be understood that changes and modifications may be made within the scope of the appended claims without departing from the spirit of the invention.

Referring now to the different drawings more in detail, in which similar characters of reference indicate corresponding parts in all the figures and referring more particularly to the preferred form of my invention selected for illustrative purposes, I have shown a receiving compartment comprising a pair of side walls 4 which diverge outwardly from their lower extremities to a point intermediate the extremities and which diverge inwardly from the said intermediate points to their upper extremities as is best shown in Fig. 3, a forward end wall 6 and a rearward end wall 8, which end walls are substantially parallel and are angularly disposed relative to the vertical axis of the compartment, and a top wall member 10.

An elongated duct generally indicated by 20 is provided in substantially horizontal position and has a pair of side walls 24 which diverge outwardly from their lower extremities to a point intermediate the extremities and which diverge inwardly from the said intermediate points to their upper extremities as is best shown in Fig. 4, a bottom wall 26 and a top wall 28. An end wall 29 at the rearmost extremity of the conduit encloses the same and may be provided with a closure 29' hinged as at 31 so as to permit entrance thereinto if desired.

An extension of the member 26 serves as the bottom wall member of the receiving compartment whereby the receiving compartment and the elongated duct are brought into adjacency. Likewise the wall members 4 and 24 may be made from single sheets of stock if desired so as to further simplify the construction of the device.

55 A wall member 30 connects the top wall 28 and

the rearward end wall member 8 in such manner as to enclose the construction whereby communication between the receiving compartment and the elongated duct is afforded.

As a special feature of the invention a circulator is provided comprising a semicircular wall member 43 and a pair of circulator side wall members 42. Member 40 is fixed at its lower extremity to the wall member 8 and has its upper extremity 41 extending slightly inwardly into the receiving compartment beyond the wall member 8. The wall member 8, it will be understood, is properly apertured so as to include the circulator within the receiving compartment. Side walls 42 are fixed to the opposite edges of the member 40 and to the member 8 so as to enclose the circulator within the receiving compartment as will be appreciated by reference to Fig. 1.

Hot air may be introduced from a source into the receiving compartment through an inlet 59 which, it will be appreciated, is urged upwardly and along the circuitous route indicated by the arrows *a*.

A damp air outlet 52 is provided in the tip member 19 for the passage therethrough of moist or damp air from the receiving compartment during operation as will shortly be explained.

The material to be dried is admitted to the device by means of inlet 54 in the wall member 40.

Entrance to the receiving compartment may be had through an opening 9 in the wall member 6 which may be closed when the device is in operation by means of a closure member 55.

A plurality of vertically spaced baffle plates 60 may be horizontally disposed within the circulator and if desired within the remainder of the receiving compartment.

These baffle plates direct the hot air and the material being dried into various paths so that a mixing of the two elements is insured. The hot air following the route designated by *a* urges the material being dried into the receiving compartment.

As a further aid to influencing the direction of the movement of the dried material vertically disposed baffles may be fixed within the receiving compartment in a manner best shown in Figs. 1 and 3.

There is provided within the member 20 a continuous conveying means comprising an endless flexible member 80 supported by a drive shaft 82 and a plurality of idler shafts 84. Sprockets 85 on the shafts engageable with the member 80 insure the movement thereof as the drive shaft 82 is rotated.

A plurality of pushers 83 spaced throughout the length of the member 80 and secured thereto are provided so that as the member 80 is moved in the direction indicated by the arrow *b* the dried material which has dropped to the bottom of the receiving compartment on the bottom wall member 26 is urged rearwardly through the elongated conduit towards the outlet 90 in the bottom wall member 26 at the rearmost extremity of the member 20 as shown in Fig. 1, from and through which discharge may be obtained.

If desired a plurality of hot air inlets 92 may be provided in the wall members 24 whereby additional hot air may be introduced to the material being dried as it proceeds toward outlet 90.

Also if desired a plurality of damp air outlets

94 may be provided to permit escape of damp air collected within the conduit 20.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

15 What it is desired to claim and secure by Letters Patent of the United States is:

1. Drying apparatus comprising in combination, a vertically disposed receiving compartment having lower, side, front and rear and upper walls, said upper wall having an outlet on the

20 upper side thereof and said forward wall having a hot air inlet on the forward side thereof adjacent the lower side thereof, an elongated conduit extending horizontally from the rear side thereof

25 having a discharge outlet at its rear end, a semi-circular circulator wall on the rear side of said compartment having an inlet for sawdust in the upper side thereof and arranged and disposed whereby hot air from said hot-air inlet is directed

30 outwardly, upwardly and rearwardly into the receiving compartment below said sawdust inlet, and movable conveying means for conveying sawdust from the receiving chamber along said conduit to the discharge outlet thereof.

35 2. Drying apparatus comprising in combination, a vertically disposed receiving compartment having lower, side, front and rear and upper walls, said upper wall having an outlet on the upper side thereof and said forward wall having a

40 hot air inlet on the forward side thereof adjacent the lower side thereof, an elongated conduit extending horizontally from the rear side thereof having a discharge outlet at its rear end, a semi-circular circulator wall on the rear side

45 of said compartment having an inlet for sawdust in the upper side thereof and arranged and disposed whereby hot air from said hot-air inlet is directed outwardly, upwardly and rearwardly into the receiving compartment below said sawdust inlet, and movable conveying means for conveying sawdust from the receiving chamber along said conduit to the discharge outlet thereof, said conveying means including an endless flexible member supported by rotatable members

55 having pushers spaced therealong.

3. Drying apparatus comprising in combination, a vertically disposed receiving compartment having lower, side, front and rear and upper walls, said upper wall having an outlet on the upper side thereof and said forward wall having a hot air inlet on the forward side thereof adjacent the lower side thereof, an elongated conduit extending horizontally from the rear side thereof

60 having a discharge outlet at its rear end, a semi-circular circulator wall on the rear side of said compartment having an inlet for sawdust in the upper side thereof and arranged and disposed whereby hot air from said hot-air inlet is directed outwardly, upwardly and rearwardly

65 into the receiving compartment below said sawdust inlet, spaced horizontal baffles in said circulator, and movable conveying means for conveying sawdust from the receiving chamber along said conduit to the discharge outlet thereof.

4. Drying apparatus comprising in combina-

tion, a vertically disposed receiving compartment having lower, side, front and rear and upper walls, said upper wall having an outlet on the upper side thereof and said forward wall having a hot air inlet on the forward side thereof adjacent the lower side thereof, an elongated conduit extending horizontally from the rear side thereof having a discharge outlet at its rear end, a semi-circular circulator wall on the rear side of said compartment having an inlet for sawdust in the upper side thereof and arranged and disposed whereby hot air from said hot-air inlet is directed outwardly, upwardly and rearwardly into the receiving compartment below said sawdust inlet, vertically disposed baffles spaced from opposite side walls of said receiving compartment adjacent said lower wall, and movable conveying means for conveying sawdust from the receiving chamber along said conduit to the discharge outlet thereof.

5. Drying apparatus comprising in combination, a vertically disposed receiving compartment having lower, side, front and rear and upper walls, said upper wall having an outlet on the upper side thereof and said forward wall having a hot air inlet on the forward side thereof adjacent the lower side thereof, an elongated conduit extending horizontally from the rear side thereof having a discharge outlet at its rear end, a semi-circular circulator wall on the rear side of said compartment having an inlet for sawdust in the upper side thereof and arranged and disposed whereby hot air from said hot-air inlet is directed outwardly, upwardly and rearwardly into the receiving compartment below said sawdust inlet, and movable conveying means for conveying sawdust from the receiving chamber along said conduit to the discharge outlet thereof, said conveying means including an endless flexible member supported by rotatable members having pushers spaced therealong, said conduit having elongated lower, side and upper walls and

said side walls diverging from said lower wall to a point intermediate said lower and upper walls and converging from said point to said upper wall.

- 5 6. Drying apparatus comprising in combination, a vertically disposed receiving compartment having lower, side, front and rear and upper walls, said upper wall having an outlet on the upper side thereof and said forward wall having a hot air inlet on the forward side thereof adjacent the lower side thereof, an elongated conduit extending horizontally from the rear side thereof having a discharge outlet at its rear end, a semi-circular circulator wall on the rear side of said compartment having an inlet for sawdust in the upper side thereof and arranged and disposed whereby hot air from said hot-air inlet is directed outwardly, upwardly and rearwardly into the receiving compartment below said sawdust inlet, and movable conveying means for conveying sawdust from the receiving chamber along said conduit to the discharge outlet thereof, said conveying means including an endless flexible member supported by rotatable members having pushers spaced therealong, said conduit having elongated lower, side and upper walls and said side walls diverging from said lower wall to a point intermediate said lower and upper walls and converging from said point to said upper wall, said conduit provided with spaced air inlet and outlet openings.
